PAIR OF SUNGLASSES

Richard L. Huggins, Lima, N.Y., assignor to Bausch & Lomb Incorporated, Rochester, N.Y., a corporation of New York

Filed July 2, 1969, Ser. No. 18,024

Term of patent 14 years

Int. Cl. D16—08

U.S. Cl. D57—1

FIG. 1

FIG. 1 is a front view of a pair of sunglasses showing my new design;

FIG. 2 is a side view of said pair of sunglasses taken from the right side thereof as viewed in FIG. 1, the side not shown being of substantially the same appearance as the side shown; and

FIG. 3 is a top plan view thereof.

The temples are shown broken away in FIG. 3 for convenience of illustration.

I claim:

The ornamental design for a pair of sunglasses, substantially as shown and described.
